E. R. BITTNER.
INTERMITTENT OPERATING MECHANISM.
APPLICATION FILED JAN. 27, 1915.

1,243,582.

Patented Oct. 16, 1917.

UNITED STATES PATENT OFFICE.

EMIL R. BITTNER, OF VICTORIA, TEXAS.

INTERMITTENT-OPERATING MECHANISM.

1,243,582.

Specification of Letters Patent. Patented Oct. 16, 1917.

Application filed January 27, 1915. Serial No. 4,709.

To all whom it may concern:

Be it known that I, EMIL R. BITTNER, a citizen of the United States, residing at Victoria, R. F. D. #3, Box 28, in the county of Victoria and State of Texas, have invented certain new and useful Improvements in Intermittent-Operating Mechanism, of which the following is a specification.

The invention has for an object to effect an improvement in automatic regulating means for wind mills, applicable to use in assuring a supply of water in a tank at a mean level without liability of too frequent operation of the control. An important aim is to give an improved and simple construction of ratchet and pawl and means for holding the pawls operative at one time and inoperative at another time.

It is also sought to give such a device as will not be easily deranged, which will not wear out quickly, and which may be produced at a low cost. Another purpose is to present an embodiment of the invention which will be applicable to use with any usual construction of windmill already in use, without modification of the original structure.

Additional objects, advantages, and features of invention will appear from the construction, arrangement, and combination of parts hereinafter set forth and shown in the drawings, where

Figure 1 is an elevation of a windmill pumping plant having the present embodiment of my invention installed thereon.

Fig. 2 is a detail of the mounting of the vane and its control.

Fig. 3 is a plan view of the control.

Fig. 4 is a detail of connections between the spider and float.

There is illustrated a tower 10 having a tank 11 of usual form thereon, supplied by any suitable pump, not shown, operated by means of the pump rod 12 connected in a familiar way with the wind wheel 13. The wheel 13 is held in operative or inoperative position by means of the vane 14 including the frame 15 pivoted on the rotating frame 16 by which the wheel 13 and the drive connections therewith are carried. The vane is held yieldably in operative position by means of the spring 17, and is drawn to inoperative position by means of the cable 18 extending around suitable pulleys 19 and thence downward through the tower to a point of control. These details are well

known in the art and do not comprise a novel part of my invention.

The point of control in the present case is a platform 20, located on the tower over the tank 11 and having suitably mounted thereon a bracket 21 upon which there is revolubly mounted a ratchet wheel 22 by means of a stub shaft 23. The outer end of this shaft also supports pivotally a spider 24, having two wiper arms 25 and 26 carrying small rollers 27 at their outer ends adjacent the perimeter of the wheel 22. The spider also includes the weight carrying arm 28, upon which there is longitudinally adjustable a weight 29 consisting of a suitable body of metal centrally bored and receiving the arm 28 slidably therethrough, a set screw being provided to secure the weight in adjusted position. The shaft 23 is extended through the bracket 21 to a second smaller bracket 31, spaced from the first bracket, a drum 32 being carried upon the shaft between the brackets. Pivoted upon these brackets there is a yoke member 33, having a lever arm 34 extended therefrom and pivotally connected to the pump rod as at 35.

The yoke has pivoted thereon a pawl 36, hanging so as to engage the ratchet under reciprocation of the pump rod, a weighted extension 37 being projected therefrom to bear the pawl against the ratchet wheel.

The pawl is provided at the side toward the spider with a lateral flange 38, extending divergently outward and upward from the arc of movement of the outer end of the arm 26 which is adjacent thereto, the flange being also alined with the plane of oscillation of the arm. The yoke is so pivoted and the pawl 36 so located thereon that reciprocation of the pump rod will operate the ratchet wheel and rotate the drum 32.

In the inoperative position of the control—that is to say, the position in which the windmill is left free to operate the pump—the weighted arm 28 is approximately or nearly vertical, resting against a checked lug 39 on the bracket 21, while the arm 26 lies with the wiper 27 thereon engaged with the flange 38 of the pawl 36 so as to hold the pawl in disengaged position, permitting the pump rod to reciprocate without operating the ratchet wheel. The arm 25 at this time is approximately horizontal, the wiper thereon being engaged with a flange 38' formed on a ratchet 40 having an inward weighted

extension 41 by which its upper part is borne inwardly toward the ratchet wheel. The arm 25 in this position holds the pawl 40 disengaged also, the flange 38' being downwardly divergent from the arc of movement of the wiper 27 on this arm. The spider is movable from this position in the direction of divergence of the pawl flanges to permit them to fall inwardly and engage the ratchet. Connected to the arm 25 there is a link 42 extending downwardly and connected to a rocking arm 43 normally horizontal, pivoted intermediately of its length on the tower frame. To the opposite end of the arm 43 a second lower link 44 is connected, extending into the tank 11, where a float 45 is engaged slidably thereon, the movement of which on the link is limited by upper and lower stops 46 secured to the link. It will be seen that when the level of the water in the tank falls to a sufficiently low point the float will engage the lower check, and when it rises a certain height the upper check will be engaged by the float. The last mentioned action will result in the link 42 pulling the spider toward disengaged position, and after the weight 29 has moved a certain distance it will fall rapidly moving the spider to entirely disengaged position, and holding it there until the weight engages the lower check when the spider will be returned to engaged position, lifting the pawls from engagement with the ratchet wheel. Connected to the drum 32 there is a cable 18, before mentioned, so that when the lower check is engaged and the ratchet and pawls held disengaged, the vane is free to move under action of the spring 17 to operative position, the wheel 12 then being held so as to be rotated by any wind of sufficient force and operating the pump to fill the tank. When the upper check 46 is engaged and the ratchet and pawl allowed to engage the ratchet wheel, the reciprocations of the pump rod will cause rotation of the ratchet wheel and drum through the agency of the yoke 33 and pawl 36, winding the cable 18 so as to draw the vane 14 to inoperative position. Any tendency of the wheel 13 then to operate will be checked by the engagement of the pawl 36 with the ratchet, by reason of the connection of the pump rod thereto and the tautening of the cable 18. The form of the connections between the float and spider may be varied to suit various conditions and types of construction with which it may be employed, and the control device may be mounted in other situations than that shown, as, for instance, it may be mounted on the top of the tank 11, and the lower link 44 connected to the arm 26 of the spider, or connections made between the spider and a float in a tank at a distance from the tower by means of suit-

able links and bell cranks, these details being sufficiently obvious not to require illustration.

It is desirable that the connection between the links 42 and the arm 25 be made with a lost motion connection, in order that as soon as the spider has been moved a little way it may fall immediately into position to allow operation of the drum, under action of the weight 29. As shown, this connection comprises a rotating pin 47 having an apertured head through which the upper end of the link 42 is slidably engaged. The link is provided with collars 49 suitably spaced thereon to permit the action described. By this arrangement the float link 44 will not require a great degree of movement in order to set the controlling mechanism into operation to stop the mill, and it will be possible to allow the tank to fill to a high point without liability of running over.

If the controlling device is located at a considerable distance from the tank, which may be found desirable to make connections with the arm 28, instead of the one 25, as dotted in Fig. 2.

In Fig. 4 there is shown a preferable construction of the connections between the spider and link 42, which consists in forming a longitudinally extending lug 50 on the arm 25, in which there is formed an oblong slot 51, through which the link is engaged. The check collars 49 are engaged upon the link above and below the lugs, as with the rotating pin previously described. Similar lugs 52 one of which is shown may be formed on the arms 26 and 28, to be used in case found desirable in making connections with a slope point.

What is claimed is:

1. An improved ratchet and pawl liquid level control device and means to check its operation, comprising a tank, water supply means therefor, a ratchet wheel, a lever pivoted thereadjacent, a pawl on the lever operative upon the ratchet at times, means tending to move the pawl to engaging position, a spider pivoted adjacent the ratchet including a wiper arm extending into proximity with the pawl, and a lateral flange on the pawl divergent from the path of the wiper in one direction, a ratchet similar to the pawl, and a second wiper arm on the spider engageable with the ratchet flange and means to operate the spider, comprising a float, lost motion connections between the float and spider, and a weight on the spider positioned to lie adjacent the vertical center line thereof, when the float is at one limit of movement, means to check movement of the weight away from said center when in the position named, the connections being constructed to move the weight across said center under movement of the float to the opposite limit of its movement, and con- 130

trol connections for said water supply means, operatively associated with said spider for the purposes described.

2. An improved ratchet and pawl device and means to check its operation, a lever pivoted thereadjacent, a pawl on the lever operative upon the ratchet at times, means tending to move the pawl to engaging position, a spider pivoted adjacent the ratchet including a wiper arm extended into proximity with the pawl, and a lateral flange on the pawl in and divergent from the path of the wiper in one direction, a ratchet similar

to the pawl, a second wiper arm on the spider engageable with the ratchet flange, a 15 weighted arm on the spider extended nearly vertically at one limit of its movement, means to check the arm at said position, and means to operate the spider including a lost motion connection.

In testimony whereof I have affixed my signature in presence of two witnesses.

EMIL R. BITTNER.
